UNITED STATES PATENT OFFICE

MARTIN I. LARSEN, OF CHICAGO, ILLINOIS

WATER HEATER

Application filed June 4, 1932. Serial No. 615,447.

This invention relates to improvements in water heaters and pertains particularly to a heater which is designed to provide hot water under pressure or which may be employed for the formation of steam for heating or other purposes.

The primary object of the present invention is to provide a heater for water having a novel means for raising the temperature of the water rapidly after the heater has been set going.

Another object of the invention is to provide a water heater wherein the heating unit is disposed within the water container or boiler and the construction is such that the heating unit may be easily and quickly removed in one body from the boiler.

The invention will be best understood from a consideration of the following detailed description taken in connection with the accompanying drawings forming part of this specification, with the understanding, however, that the invention is not confined to any strict conformity with the showing of the drawings but may be changed or modified so long as such changes or modifications mark no material departure from the salient features of the invention as expressed in the appended claims.

30 In the drawings:—

Figure 1 is a vertical sectional view through the water heater embodying the present invention;

Figure 2 is a transverse sectional view taken on the line 2—2 of Figure 1;

Figure 3 is an enlarged sectional view taken on the line 3—3 of Figure 1;

Figure 4 is a sectional view taken substantially upon the line 4—4 of Figure 2;

40 Figure 5 is a sectional detail showing the connection of a water tube with the inner casing.

Referring now more particularly to the drawings wherein like numerals of reference indicate corresponding parts throughout the several views, the numeral 1 indicates as a whole a tank which is of sufficient strength to contain water under pressure or steam. This tank is preferably substantially elliptical in cross section, although it is to be understood

that any other cross sectional design may be employed without departing from the spirit of the invention. The tank 1 has a bottom 2 which rests upon a supporting base 3.

The bottom 2 is provided with an opening 4 adjacent one end of the tank body and extending upwardly through this opening and into the tank is a casting which is indicated generally by the numeral 5. This casting comprises a head portion 6 which is generally circular in cross section and has the longitudinally extending central chamber 7. The inner and outer surfaces of the wall of the head 6, are longitudinally fluted as indicated at 8 and these walls which are relatively thick as shown in Figures 1 and 3, have extending longitudinally therethrough from the top a plurality of vertical passages certain of which are indicated by the numerals 9, while the others are indicated by the numerals 9'. Each of these passages 9 and 9' communicates at its lower end with a lateral passage 10 which opens outwardly through the wall of the head 6 as illustrated in Figures 1, 3 and 4.

The central portion of the head 6 has an opening 11 which communicates with the chamber 7 and the lower part of the chamber 7 opens to the full extent of its diameter into the small upper end of a substantially frusto-conical hollow base 12. The lower edge of this hollow frusto-conical base portion is also open and surrounding the edge thereof and projecting laterally is a flange 13 which positions against the under side of the tank bottom 2 to which it is secured by suitable means, such for example, as the bolts 14.

Secured in the upper end of each of the vertical passages 9 is a straight upright water circulating pipe 15 while each of the passages 9' has secured in its upper end one end of a water pipe 16 which curves outwardly and downwardly with respect to the head 6 and is then curved further to extend substantially circumferentially of the head 95 as indicated at 17 so that its other end will terminate in a horizontal plane passing through the upper portions of the lateral passages 10 and in a vertical plane passing between two of these lateral passages which 100

are in communication with vertical passages 9.

The opening 11 in the top of the heating unit head 6 has a flue pipe 18 secured there-in which passes upwardly through the top of the tank 1 as shown. A suitable packing such as is indicated at 19, surrounds the flue pipe 18 to prevent leakage of the contents of the tank at this point.

10 Disposed vertically in the tank and having the flue pipe passing axially therethrough is a relatively long cylinder 20 which encases the vertical tubes 15 and has their upper ends passing through the top 21 thereof as indicated at 22 and shown in detail in Figure 5. The central part of the top 21 is provided with an opening surrounded by a collar 23 through which the flue pipe 18 passes.

The lower end of the cylinder 20 is open 20 and has secured therein the ring 24 which is connected with the curved free ends 17 of the return flow pipes 16.

Disposed within the base portion of the heater is a burner 25 which is located directly beneath the open lower end of the cone base 12, by means of which heater the temperature of the contents of the tank is raised. At the end of the tank opposite that in which the heating unit 5 is disposed, is a water inlet 26 with which is connected a return flow pipe 27 and disposed transversely of the tank and connected with the side walls and the bottom thereof, is a baffle plate 28 which prevents the water flowing in through the pipe 35 26 from immediately contacting with the heating unit 5. As shown, this baffle plate 28 is inclined toward the adjacent end of the tank away from the heating unit so that the inflowing water will rise to a considerable 40 height in the tank before it comes into contact with the heating unit or the cylinder surrounding the flow tubes.

The top of the tank is provided with a suitable outlet pipe as indicated at 29 and the 45 side wall adjacent the top has connected therewith a water level indicating glass 30 and a pressure indicator 31 by means of which latter instrument the internal pressure of the boiler may be readily determined.

50 From the foregoing description it will be readily apparent that after lighting the burner 25 the water in the tubes 9 and 9' will be raised in temperature and that located in the tubes 9' will immediately flow out and 55 down to the lateral passages 10 which form the inlets for the passages 9 which communicate with the vertical tubes 15.

This passage of heated water outside of the head 6 and at the entrance to the passages 9 60 will materially facilitate the establishment of the desired circulation of water upwardly through the tubes 15 and, therefore, cause the temperature of the contents of the boiler to be rapidly raised. By providing the cylinder 65 20 around the tubes the chilling of the

heated water passing upwardly therethrough is prevented by direct contact therewith of water flowing into the tank.

It will be apparent from the foregoing that 70 in a tank constructed in accordance with the present invention the temperature of the water therein will be rapidly raised with a minimum expenditure of fuel.

Having thus described the invention, what 75 is claimed is:—

1. A water heater, comprising a tank, a chambered heating unit mounted within said tank upon the bottom and opening through the bottom thereof, flue means for removing gases from the said heating unit, water passages formed vertically in the wall of said unit and opening at their lower ends laterally into the tank, water circulating tubes extending vertically from the upper ends of certain of said passages, means for conducting water from the upper ends of certain others of the passages back to the said lateral ports leading into the first mentioned passages, a heating element disposed in the lower end of said unit, and water inlet and outlet means for the tank.

2. A water heater of the character described, comprising a tank having a bottom provided with an opening, a chambered heating unit having a lower open end and mounted upon said bottom to open downwardly through the opening therein, water heating passages formed vertically in the wall of said heating unit and opening through the top thereof and communicating at their lower ends with laterally directed inlet ports, vertically disposed water circulating tubes connected at their lower ends with the upper ends of certain of said passages, means for conducting water from the upper ends of the other of said passages downwardly across the outside of the heating unit to the inlet ports leading to the passages connected with the vertical tubes, a heating element in the lower open end of the heating unit, a flue pipe connected with the upper end of said unit, and water inlet and outlet means for the tank.

3. A water heater comprising a tank having a bottom provided with an opening, a heating unit comprising a substantially frusto-conical hollow cone open at its lower end and having the said lower end secured in the said tank bottom opening, a hollow head forming the upper part of the heating unit and in communication with the upper end of the frusto-conical body, said head having a relatively thick wall provided with a plurality of vertical passages each opening at its upper end through the top of the head and at its lower end opening laterally through the side wall into the tank, water circulating tubes disposed vertically above the head and connected at their lower ends with certain of said passages, water return flow tubes connected with the others of the passages and arranged

to conduct water downwardly for discharge at the laterally opening lower ends of those passages connected with the vertical tubes, a heating element disposed beneath the open 5 lower end of the frusto-conical body, a flue connected with the interior of said head, and water inlet and outlet means for the tank.

4. A water heater comprising a tank having a bottom provided with an opening, a 10 heating unit comprising a substantially frusto-conical hollow cone open at its lower end and having the said lower end secured in the said tank bottom opening, a hollow head forming the upper part of the heating unit 15 and in communication with the upper end of the frusto-conical body, said head having a relatively thick wall provided with a plurality of vertical passages each opening at its upper end through the top of the head and 20 at its lower end opening laterally through the side wall into the tank, water circulating tubes disposed vertically above the head and connected at their lower ends with certain of said passages, water return flow tubes 25 connected with the others of the passages and arranged to conduct water downwardly for discharge at the laterally opening lower ends of those passages connected with the vertical tubes, a heating element disposed beneath 30 the open lower end of the frusto-conical body, a flue connected with the interior of said head, water inlet and outlet means for the tank, and a cylinder disposed vertically in the tank and surrounding said tubes and 35 having its upper end closed and the tubes passing therethrough and further having its lower end open.

5. A water heater comprising a tank having a bottom provided with an opening, water 40 inlet and outlet means for the tank, a heating unit comprising a hollow substantially frusto-conical body open at its lower end and secured about the lower edge in said bottom opening, a hollow head mounted 45 upon the upper end of the frusto-conical body and opening downwardly thereinto, said head having an opening in its upper end, a flue passage connected with the aperture in the upper end of the head and leading to 50 the exterior of the tank, said head having a side wall of substantial thickness and having vertically disposed passages formed in said side wall from the top downwardly to a point adjacent the bottom of the head and opening 55 laterally through the outer side thereof into the tank, a plurality of vertically disposed tubes connected at their lower ends in the upper ends of certain of said passages, a plurality of down flow tubes each connected at 60 one end in the upper end of a remaining one of said passages and curved outwardly and downwardly and circumferentially across the outer wall of the head and terminating adjacent the lower inlet ends of a pair of passages leading to the vertical tubes, a cylinder 65

disposed vertically in the tank and surrounding said tubes, said cylinder being closed at its upper end and having the upper ends of the vertical tubes opening therethrough, the lower end of the cylinder being open, and a heating element disposed beneath the open lower end of the frusto-conical body. 70

6. A water heater comprising a tank having an inlet and an outlet, a chambered body within the tank and opening at one side through a wall of the tank to receive heat from a burner element, said chambered body having a flue leading therefrom to the exterior of the tank, a plurality of passageways formed in the wall of the chambered body and having inlet and outlet ends, and means for creating a circulation of water between the outlet ends of certain of the passageways and the inlet ends of the other passageways. 75

7. A water heater comprising a tank having an inlet and an outlet, a bottom wall, a chambered body having an upper portion and a lower portion, the said upper portion having a relatively thick wall and the lower portion being of substantially frusto-conical formation and opening downwardly through the bottom of the tank, and a heating element disposed beneath the open lower portion of the body, water circulating passageways formed in the thickened wall of the upper portion and having lower inlet ends and upper outlet ends, and means for conducting water from the outlet ends of certain of the passages back to the lower inlet ends of adjacent passages. 80

8. A water heater comprising a tank having a bottom wall and an inlet and an outlet, a body disposed within the tank having an upper portion and a lower portion, said portions of the body being hollow and said lower portion being substantially frusto-conical and opening at its lower end through said bottom wall, said upper portion having a plurality of vertical water circulating passages in its wall open at their upper and lower ends, a heating element beneath the lower portion of the body, an exhaust flue connected with the upper portion of the body, and a plurality of return flow pipes each connected at one end in the upper end of a water passage and extending downwardly and in a circumferential direction with respect to the upper portion of the body and terminating adjacent the lower inlet end of an adjacent water passage. 85

9. A water heater comprising a tank having a bottom wall and an inlet and an outlet, a body disposed within the tank having an upper portion and a lower portion, said portions of the body being hollow and said lower portion being substantially frusto-conical and opening at its lower end through said bottom wall, said upper portion having a plurality of vertical water circulating passages in its wall open at their upper and 90

lower ends, a heating element beneath the lower portion of the body, an exhaust flue connected with the upper portion of the body, a plurality of return flow pipes each connected at one end in the upper end of a water passage and extending downwardly and in a circumferential direction with respect to the upper portion of the body and terminating adjacent the lower inlet end of an adjacent water passage, a casing enclosing the upper portion of the body and open adjacent the lower part thereof and closed above the body, and water conducting tubes connected with the upper ends of the said adjacent water passages and extending to and opening through the closed upper portions of the casing.

10. A water heater comprising a tank having an inlet and an outlet, a bottom wall, 20 a chambered body having an upper portion and a lower portion, the said upper portion having a relatively thick wall and the lower portion being of substantially frusto-conical formation and opening downwardly through 25 the bottom of the tank, a heating element disposed beneath the open lower portion of the body, water circulating passageways formed in the thickened wall of the upper portion and having lower inlet ends and 30 upper outlet ends, means for conducting water from the outlet ends of certain of the passageways back to the lower inlet ends of adjacent passageways, a casing enclosing the said upper portion of the body and being open 35 adjacent the lower part of the body and closed above the body, and water tubes extending from the said adjacent water passageways of the body through the closed top of the casing.

40 11. In a water heater, a hollow body designed to be placed in a tank, means for heating the interior of said body, fluid circulating passages formed about said body and in communication at their ends with the contents of the tank, and means for directing the fluid issuing from an end of certain of the passages back to the inlet ends of the other passages.

In testimony whereof I hereunto affix my
50 signature.

MARTIN I. LARSEN.
